BED AND PLATEN PRINTING PRESS AND INKING MECHANISM THEREFOR.

APPLICATION FILED JUNE 23, 1906.

3 SHEETS—SHEET 3.

UNITED STATES PATENT OFFICE.

FRANCIS MEISEL, OF BOSTON, MASSACHUSETTS, ASSIGNOR TO MEISEL PRESS & MANUFACTURING CO., OF BOSTON, MASSACHUSETTS, A CORPORATION OF MASSACHUSETTS.

BED-AND-PLATEN PRINTING-PRESS AND INKING MECHANISM THEREFOR.

No. 866,290.

Specification of Letters Patent.

Patented Sept. 17, 1907.

Application filed June 23, 1906. Serial No. 323,029.

To all whom it may concern:

Be it known that I, FRANCIS MEISEL, a citizen of the United States, residing at Boston, in the county of Suffolk and State of Massachusetts, have invented a new and useful Bed-and-Platen Printing-Press and Inking Mechanism Therefor, of which the following is a specification.

My invention relates to improvements in bed and platen printing presses and inking mechanism therefor; 10 the principal objects being to provide for running at a high rate of speed, using type forms with safety; for efficiently applying ink to the type forms; also to provide for connecting the inking mechanism with the apparatus for operating the press in such a manner that 15 the inking mechanism will operate constantly independently of the position of the bed or beds.

Further objects and advantages of the invention will appear below.

Reference is to be had to the accompanying drawings which constitute part of this specification, in which

Figure 1 is a side elevation of a bed and platen printing press showing one form of my invention applied thereto. Fig. 2 is an enlarged view of certain parts of 25 the same, showing additional details of construction. Fig. 3 is a side elevation of the crank-shaft, and Fig. 4 is a plan of a portion of the press with my improvement applied.

The machine is provided with a movable bed or beds 30 having horizontal faces on which the type form rests, so that the paper can be printed on one or both sides.

Mechanism is provided for operating the bed or beds continuously, also an inking mechanism having a continuous rotary motion mounted on the reciprocating 35 bed or beds and moving therewith. The inking mechanism is connected with the apparatus for operating the parts in such a manner that it will operate continuously independently of the position of the beds.

The paper or other web material to be printed is 40 taken from a roll 10 over guide rollers 11, under a platen 12, over additional guide-rollers, and then under a platen 13, being printed on opposite sides when under the two platens.

In the operation of printing, a crank shaft 14 is ordinarily employed, this shaft having an arm 15 for raising and lowering the frame 16, carrying beds 17 and 18 for operating against the platens 12 and 13 respectively. Located on the frame 16 and therefore moving with it, I have mounted bearings 19 for shafts 20, these shafts 50 carrying sprocket wheels 21. Also located on this frame are a pair of shafts 22 which carry sprocket wheels 23, the latter sprocket wheels being loosely mounted on their shafts and turning independently thereof. The two sets of sprocket wheels are connected by

chains 24 which carry an inking or ink applying device, 55 preferably in the form of a plurality of rollers 25. These inking rollers obviously are adapted to move over the surface of the beds 17 and 18, and also to travel around a pair of large inking rollers 26 which are keyed to the shafts 22, and consequently rotate with these shafts. 60

In order to rotate the large inking rollers in one direction and the chains in another, and to give rotation to these parts at all times when the shaft 14 is operating independently of the location of the beds, I have provided the following mechanism. On the shaft 14 is 65 located a gear 27. With this gear meshes a gear 28 connected by gear 29 with a gear 30 on the lower shaft 20. This gear is connected by an intermediate gear 31 with a gear 32 on the upper shaft 20. The gears 28 and 29 are mounted in bearings on arms 33 pivotally mounted 70 on the lower shaft 20, and adapted to fall by their own weights sufficiently to keep the gear 28 in mesh with the gear 27 when the frame 16 rises and falls with the shaft 20. On the shaft 14 is also mounted another gear 34. This gear meshes with a gear 35 which is mounted 75 in bearings on an arm 36 pivoted on the lower shaft 22 which carries a gear 37 meshing with the gear 35. The upper shaft 22 is operated from the gear 37 through an intermediate gear 38 and a gear 39 on the upper shaft 22. This part of the device operates in the same manner as the part on the other side, but the shaft 22 rotates in a direction opposite to that of the sprocket wheels thereon, which are driven from the shaft 20.

In order that gravity need not be depended upon for keeping the gears 35 and 28 in mesh with the gears 34 85 and 27 respectively, a pair of links 40 and 41 are employed to connect the concentric portion of the shaft 14 with the ends of the arms 36 and 33. In addition to these motions a crank rod 42 is connected with one of the shafts on the frame 16, this rod operating a bell-crank 43 which, through the instrumentality of a collar 44, reciprocates the shafts 22.

It will be understood, of course, that ink is applied to the large inking rollers 26 in any desired way, as for example by means of ductor rollers 45 which are 95 mounted to swing on shafts 46 as pivots, and are operated through connections 47 by a cam 48 on the shaft 14.

It is to be understood that while I have illustrated and described one particular embodiment of my invention, the same is not limited thereto in details of construction, as many modifications can be made by a person skilled in the art without departing from the scope of my invention as expressed in the claims.

Having thus fully described my invention, what I 105 claim and desire to secure by Letters Patent is:—

1. An inking device for printing presses comprising a pair of shafts journaled on a movable frame, an inking

- roller connected with one of said shafts, inking members connected with the other shaft, said inking members being adapted to move into contact with said roller, means for moving said inking members in one direction, and means 5 for moving the contacting surface of the roller in the opposite direction.
2. An inking device comprising two shafts, wheels thereon, an endless carrier supported by said wheels, an inking member on said carrier, an additional inking roller 10 on one of said shafts adapted to contact with said inking member during part of its orbital movement, means for moving said endless carrier, and means for rotating said additional inking roller.
3. An inking device for a printing press comprising an 15 endless carrier, inking rollers mounted to travel therewith, an additional inking roller with which the first named rollers are adapted to engage located within the boundaries of said carrier and between the strands thereof, and means for moving said carrier and additional inking roller 20 in such a manner that the carrier moves in one direction and the contacting surface of the inking roller moves in the opposite direction.
4. An inking device for bed and platen presses, comprising an endless chain, inking rollers mounted thereon, an 25 additional inking roller with which the first named rollers are adapted to engage, and means for moving said chain and the adjacent surface of said additional inking roller in opposite directions.
5. An inking device for bed and platen printing presses 30 comprising a carrier, inking members carried thereby, an inking roller with which said inking members are adapted to engage, means for moving said carrier, and means for rotating said inking roller in such a way that its surface adjacent to the inking rollers will move in a direction 35 opposite to their motion.
6. An inking device comprising two shafts, wheels thereon, an endless carrier on said wheels, an inking member on said carrier, an additional inking roller fixed to one of said shafts and adapted to contact with said inking member 40 during part of its orbital movement, the carrier being positively driven from the other of said shafts, and means for rotating said shafts in opposite directions.
7. An inking device, comprising a pair of sprocket 45 wheels, a chain connecting said sprocket wheels, means for rotating one of said sprocket wheels, an ink applying device mounted on said chain and traveling therewith, a shaft on which the second sprocket wheel is mounted to freely rotate, an inking roller keyed to said shaft, and means for rotating said inking roller in a direction opposite to that in which the sprocket wheel on said shaft rotates.
8. In an inking device, the combination of two shafts, a 50 sprocket wheel keyed to one shaft, a second sprocket wheel loosely mounted on the other shaft, a chain connecting said sprocket wheels, an ink applying device carried by said chain, an inking roller keyed to the second shaft, and means for rotating said shafts in opposite directions.
9. In an inking device, the combination of a bodily movable frame, two shafts journaled thereon, a sprocket wheel 55 keyed to the first shaft, a sprocket wheel on the second shaft, a chain connecting said sprocket wheels, an ink applying device mounted on the frame, an inking roller keyed to the second shaft, an operating shaft journaled in stationary bearings, and means for transmitting motion in 60 opposite directions to the two shafts independently of the location of said frame with respect to the said stationary bearings.
10. In a bed and platen printing press, the combination of an operating crank shaft, two gears thereon, a movable 65 frame, means connected with said crank shaft for moving said frame, a pair of shafts journaled on said frame, an inking device connected with one of said shafts, an inking roller connected with the other shaft, said inking device being adapted to move into contact with said roller, and 70 means for moving said roller and inking device in opposite directions, said means comprising a train of gearing in
- mesh with each of said gears on the crank shaft, and means for maintaining said gearing in mesh with said gears in all positions of the frame.
11. In a bed and platen printing press, the combination 80 of a crank shaft, a movable frame, a link connecting the crank shaft with the frame for moving it, two gears on the crank shaft, two gears journaled on the frame, two arms pivotally mounted on the frame, each arm being adapted to swing about the center of one of said gears, a gear on each arm adapted to mesh with one of the gears on the crank shaft and to transmit motion to one of the gears on the frame, and two links connected with the crank shaft and each connected with one of said arms for holding the gears on said arms in engagement with the gears 85 on said shaft.
12. In a bed and platen printing press, the combination 90 of a shaft, a movable frame, means connected with said shaft for moving said frame, an inking device mounted on the frame and movable therewith, means on the frame for operating said inking device, comprising a gear movable with the frame, an arm pivotally mounted on said frame on the center of said gear, a gear mounted on the arm and adapted to transmit motion to the gear on the frame, a gear on said shaft meshing with the gear on the arm, and a link connecting said shaft with said arm and holding the gear on the arm in constant engagement with the gear on the shaft during the motion of the frame.
13. In a bed and platen printing press, the combination 95 of a shaft, a reciprocable frame, beds on said frame, means connected with said shaft for moving the frame, inking devices connected with the frame and movable therewith, means for operating the inking devices to give a continuous rotary traveling motion while the beds reciprocate, movable ductor rollers, and means for moving the ductor 100 rollers toward the inking devices when the beds are in a certain position.
14. In a bed and platen printing press, the combination 105 of a shaft, a reciprocable frame, a bed connected with said frame, means connected with the shaft for moving the frame, an inking device connected with the frame and movable therewith, means for operating the inking device to move it independently of the movement of the frame, a cam connected with said shaft, a pivotally mounted ductor roller, and connections between said cam and ductor roller 110 for moving the roller toward the inking device when the latter is in a certain position.
15. An inking device comprising a bodily movable carrier, an inking member thereon, a movable member for supplying ink to the inking member, and means for moving said carrier and said movable member in such a way 115 that their adjacent surfaces always move in opposite directions.
16. In a printing press, the combination of a reciprocable frame, a plurality of beds thereon, a plurality of 120 inking devices connected with said frame and movable therewith, means on said frame for operating the inking devices to give them a continuous orbital motion about said beds, said beds being provided with faces on which the type forms rest, and a plurality of inverted platens co-operating with said beds.
17. In a printing press, the combination of two inverted 125 stationary platens, two reciprocatory beds adapted to move in contact with said platens, two inking devices connected with said beds and movable therewith, means connected with said beds for simultaneously operating said inking devices to give them a continuous orbital motion about the beds, and means for guiding a web of material to be printed upon, first under one of said platens then around a guide and back under the other platen, whereby 130 the web may be printed on both sides.
- In testimony whereof I have hereunto set my hand, in the presence of two subscribing witnesses.
